UNITED STATES PATENT OFFICE.

ALBERT H. GARRISON, OF MILWAUKEE, WISCONSIN, ASSIGNOR TO THE
BRAND STOVE COMPANY, OF SAME PLACE.

DESIGN FOR A STOVE OR RANGE.

SPECIFICATION forming part of Design No. 27,358, dated July 13, 1897.

Application filed June 1, 1897. Serial No. 639,057. Term of patent 7 years.

To all whom it may concern:

Be it known that I, ALBERT H. GARRISON, a citizen of the United States, residing at Milwaukee, in the county of Milwaukee and State 5 of Wisconsin, have invented and produced a new and original Design for Stoves or Ranges; and I do hereby declare the following to be a full, clear, and exact description of the same, reference being had to the accompanying 10 drawing, forming a part thereof.

The said drawing is a perspective view of a stove or range, showing my design.

My design has especial reference to the ornamentation upon the various portions of my 15 said stove or range, and the leading features of said design are found in the parts herein-after particularly specified, and pointed out in the claims.

The skirt ornamentation includes a plain 20 central panel or boss 1 and plain bosses 2 3, adjacent to the ends of said skirt portion. The said central panel 1 is bounded on the under side by opposing diadelphous scrolls 4 5, above which the said central panel is 25 extended longitudinally, terminated by opposing semicircular scrolls 6 7, while the upper borders of said central panel are formed by a rounded concave figure 8, having double-scroll ends. The end bosses 2 3 are sur- 30 rounded by serrated scrolls 9 10, with inwardly-extending branch scrolls of a general ogee shape, the lower branches being larger than the upper branches and serrated on the under side. The legs have smooth rounded 35 bosses 11 11 on their upper outer portions surrounded by irregular ornamental scrolls 12 12, having independent downward-extending scrolls leading therefrom terminating in convoluted ends 13, the lower portions of the legs 40 presenting otherwise smooth convex outer surfaces with marginal ribs 14 and duplex curved irregular bosses 15 at the feet thereof and the upper portions of the said legs adjacent to the scrolls surrounding the bosses being ornamented with smaller bosses and series 45 of laminated scrolls.

The oven-door is provided with four corner panels or bosses 16 17 18 19, differing one from the other in shape and size and each 50 surrounded by a border or frame of variegated

scrollwork foliated and serrated irregularly, as shown. The scrollwork borders that surround the bosses 16 and 17 approach each other at the top of the door, but without touching, leaving a distinct space between 55 their adjacent ends, while the inner ends of the scrollwork borders around the lower bosses 18 and 19 are centrally united, and said lower scrollwork borders are also united to the lower portions of the said upper scroll- 60 work borders. The branches or extensions of the described four boss borders on the oven-door are so arranged that each border is within an oblique corner line, and in this central practically lozenge-shaped space thus left 65 is an irregular oblong-shaped ornamental scroll frame 20, which forms the frame of the name-plate.

The side plate of the reservoir-casing is or- 70 namented with four panels or bosses 21 22 23 24, differing in size and shape and surrounded by scrollwork borders of irregular pattern variously foliated and serrated, but disposed so as to give continuous contact all around said plate and leave an irregular oblong ver- 75 tically-disposed inner space. The lower left-hand boss 23 is the largest of the four on said reservoir-casing, and below the same the angular continuation of said casing-plate is or- 80 namented with a continuation of said scroll- 85 work.

The fire-pot door has a large irregular panel or boss 25, surrounded by a frame or border of scrollwork irregularly serrated or foliated, with a smaller boss 26 in the left central por- 85 tion of said border and another small boss 27 in the upper right-hand end of said door. Below this door the plate or casing of the ash- 90 pit section is ornamented with a large irregular boss 28, surrounded by an irregular scroll- 90 work border, and below this still another boss 29, with a scrollwork border around the same and irregular scrollwork figures to the right of the last-named boss filling up the space be- 95 low the border of boss 28 and completing the ornamentation of said ash-pit section.

What I claim is—

1. In a design for a stove or range, the de- 100 sign for the leg, substantially as shown and described.

2. In a design for a stove or range, the design for the skirt, substantially as shown and described.
3. In a design for a stove or range, the design for the lower portion, comprising the skirt and legs, substantially as shown and described.
4. In a design for a stove or range, the design for the oven-door substantially as shown and described.
5. In a design for a stove or range, the design for the side plate of the reservoir, substantially as shown and described.
6. In a design for a stove or range, the design for the fire-pot door, substantially as shown and described.
7. In a design for a stove or range, the design for the side plate of the ash-pit section, substantially as shown and described.
8. The design for a stove or range, substantially as shown and described.
- In testimony whereof I affix my signature in presence of two witnesses.

ALBERT H. GARRISON.

Witnesses:

H. G. UNDERWOOD,
B. C. ROLOFF.
